UNITED STATES PATENT OFFICE.

BENJAMIN W. HURD, OF SAN FRANCISCO, CALIFORNIA, ASSIGNOR TO TURBINE FUEL OIL BURNER CO., OF SAN FRANCISCO, CALIFORNIA, A CORPORATION OF NEVADA.

OIL BURNER.

Application filed July 20, 1921. Serial No. 486,201.

To all whom it may concern:

Be it known that I, BENJAMIN W. HURD, a citizen of the United States, residing at San Francisco, in the county of San Francisco and State of California, have invented a new and useful Improvement in Oil Burners, of which the following is a specification.

My invention relates to improvements in oil burners, in which a rotating cup mounted on suitable bearings, driven at high speed by the means of air, steam, or other gases; distributes on the inside of the cup a thin film of oil which is mixed with air, steam, or other gases after leaving the cup, at which time it is ignited and burns; the object of my invention is to provide a burner which can be mounted either horizontally or vertically and one that will swing in and out in either position with the barrel or nozzle traveling approximately parallel with the axis of the opening in the fire-box and one that will automatically shut off the oil when the burner is withdrawn; in so doing dispensing with all flexible pipes now used to conduct the fuel oil to the burner; also to provide a way for lubricating the ball bearings by means of a combined reservoir and separator.

Referring to the accompanying drawings which illustrate the invention, Fig. 1 is a side elevation of the burner partly broken away, showing the burner in forward or firing position; Fig. 2 is a rear elevation showing upper oil joint in section; Fig. 3 is a side elevation showing burner withdrawn from firing position; Fig. 4 is an enlarged view of upper oil joint showing the shut-off position of the joint; Fig. 5 is an enlarged view of the ball bearing mounting showing the oil reservoir and feed tube leading to the reservoir.

Similar numerals refer to similar parts throughout the several views. The casting 1, with thread 8, for air, steam or gas connection; and thread 9, for oil connection comprises the base for the burner; to this is clamped air, steam or gas link 2, and oil elbow 10, by means of strap 3, and bolts 5 and 6, held by nuts 7, and kept properly spaced by spacing sleeves 4. Adjustment for wear is taken care of by means of screws 11 and 12, which are locked in place by nuts 13 and 14. Air, steam or gas link 2, has a butterfly valve 15, mounted on a stem 16,

and held by screw 17; friction to hold valve in place is through spring 20, which is held in place by washer 18, and pin 19. The upper end of air, steam or gas link 2, is hinged to the elbow 21, by screw pins 22, and 23, and is locked in place by wing nut 24. To oil-elbow 10, is screwed pipe 25, which with oil joint 26 and 27, forms the oil link. Oil joints 26 and 27, are held together by a thread on the end of 27; the nut 29, screws 65 against washer 30; the washer 30, and nut 29, turning with 27. When in firing position hole 34, in 26, registers with hole 33, in piece 27, allowing the oil to pass through; when withdrawn the holes 33 and 34, do not 70 register so no oil can pass to the burner; screw 28, is for cleaning purposes. The hollow stationary shaft 32, passes through elbow 21, and is locked in position by nut 31, and is screwed into piece 27; this construction allows elbow 21, to travel in a line 75 parallel to the axis of the hole in the fire-box by the swinging action of links 2, and 25.

To the inside end of 32, is fastened a ball bearing container 39, which is supported on the outside by perforated plate 40. Inside this container is mounted on ball bearings 43 and 51, a hollow shaft 44, on the end of which is fastened atomizing cup 49, and 80 driving wheel 53, which has numerous angular cuts or vanes on the outer surface. The bearings are held on to the shaft by nut 50, screwing against the inside race of 51, clamping the inside race of 43, against the 85 shoulder of 44, by means of separator 41, the outer race of 51, is clamped against a shoulder 54, by the oil reservoir and separator 52, which in turn is held by the outer race of 43, which is held by locknut 45; 90 locknut 45, is prevented from working loose by screw 46. The reservoir 52, receives its oil through pipe 38, and hole 37, in handle 36; handle 36, has oil cup 35, screwed into the top. Nozzle 48, is screwed to the elbow 100 21, and incloses cup 49, and ball bearing container 39; tube 47, leads fuel oil to cup.

To operate, wingnut 24, is loosened and burner rocked forward to position as in Fig. 1, when wingnut 24, is tightened, holding burner in place. To withdraw burner loosen wingnut 24, and pull back on handle 36; burner will then take the position as in Fig. 3, shutting off the fuel oil through the action of holes 33 and 34, in pieces 27 and 105 32.

26. It will be observed that the link connections 2 and 25 are illustrated in the drawings as broken and it is preferred that these members be of such length as to provide an equal distance between the pivot points 9 and 33, and 8 and 22, whereby the burner in its movement to or from active firing position has imparted thereto a substantially straight line of movement.

10 The invention claimed is:

1. In combination with an oil burner including a support, a tubular burner body, a fuel channel extending longitudinally thereof, a burner cup rotatably mounted in said nozzle and into which said channel discharges, and a pair of supporting pipes pivotally mounted at their inlet ends to said support, and at their discharge ends pivotally mounted respectively to said burner for supplying air thereto and the other to said channel for supplying oil thereto, said pivotal connections being disposed in a plane substantially in alignment with the longitudinal axis of the burner, said pipes providing a parallel link mounting for said burner affording a means whereby the burner when moved into and from active firing position is maintained in a substantially horizontal position.
2. An oil burner including a base, a burner supported thereby and including a fluid pressure actuated rotatable burner cup, a fluid channel within the burner and leading to the cup, a pair of pipes pivotally mounted at their inlet ends one in advance of the

other on said base and at their discharge ends pivotally connecting one in advance of the other with said burner, one for supplying air to the burner and the other for supplying fuel to the channel, said pipes affording a pivoted link support for the burner.

3. An oil burner including a tubular burner body, means for supplying oil and air thereto, said means including a pair of pipes pivotally connected one in advance of the other at one end to the burner and at their opposite ends to a support, one pipe affording an air supply and the other an oil supply, said pipes affording an oscillating frame support for the burner whereby the burner is maintained in a substantially horizontal path in its movement to or from active firing position.

4. An oil burner including a tubular burner body, means for supplying oil and air thereto, said means including a pair of pipes pivotally connected one in advance of the other at one end to the burner and at their opposite ends to a support, one pipe affording an air supply and the other an oil supply, said pipes affording a link support for the burner whereby a substantially straight line movement is imparted to the burner in its movement to or from active firing position.

BENJAMIN W. HURD.
